METHOD AND APPARATUS FOR FRACTIONATING HYDROCARBON OILS

Filed Jan. 27, 1928

UNITED STATES PATENT OFFICE

FRANK W. HALL, OF PORT ARTHUR, TEXAS, ASSIGNOR TO THE TEXAS COMPANY, OF NEW YORK, N. Y., A CORPORATION OF DELAWARE

METHOD AND APPARATUS FOR FRACTIONATING HYDROCARBON OILS

Application filed January 27, 1928. Serial No. 249,804.

This invention relates to the conversion of higher boiling hydrocarbon oils into lower boiling ones, and has special reference to a cracking process and apparatus of the so-called coil and drum type in which the oil is decomposed or cracked by rapidly raising the temperature thereof in transit through a heating coil and then delivering it into an enlarged drum or chamber in which cracking temperatures and pressures are maintained, and relates more specifically to that part of the apparatus and method or process called the separators, fractionating towers, dephlegmators or bubble towers, which will be hereinafter called bubble towers, wherein the vaporous products emerging from the drum or another bubble tower are received and the lighter constituents separated from the heavier constituents, the lighter constituents passing off in vapor form, preferably for further processing, and the heavier ones condensing and dropping to the bottom of the tower, thereafter being withdrawn preferably for recycling through the system.

Having in mind the ultimate evolution of refined hydrocarbon products for commercial distribution, and knowing that one of the important steps in the processing of said products is the separation, fractionation or rectification of the total constituents, the present invention is intended to accomplish such fractionation in a close and definite manner, thus making available the lighter constituents in vapor form preferably for further processing, and the heavier constituents in liquid form which may be further processed or recycled through the system.

There are certain natural drawbacks to be encountered in the removal or separation of the vaporous lighter constituents from the heavier, such as the tendency of the lighter constituents to dissolve in the heavier constituents which latter ones continually condense and collect in a body in the bottom of the bubble tower, and the inability to ordinarily maintain a sufficiently high operating or running temperature to effect liberation in the bubble tower of all of the lighter constituents from the heavier while preventing the heavier constituents from being carried

over in part by the lighter vaporous constituents.

In connection with the coil and drum type of apparatus, I also have in mind that while carrying a pressure of several atmospheres in the heating coil and drum, it may be desirable to carry a lesser pressure in the bubble towers, realizing that by progressively reducing the pressure a readier liberation of the lighter constituents from the heavier constituents may be effected.

One of the objects of the present invention is to provide a method and apparatus of the general character of the coil and drum type in which the heat employed for cracking the oil is imparted to the oil in transit through the heating coil, a cracking temperature is maintained in the drum, and a desired temperature is maintained on the heavier and lighter condensed constituents reposing in a regulated volume in the bottom of the bubble tower whereby a closer fractionation of the products may be effected. Such lighter constituents as may have mingled with the heavier and become condensed, being continuously subjected to additional heating, may be vaporized, and rising in the tower, commingle with the uncondensed lighter vapors, and emerging from near the top of the tower, continue through the system in course of process.

Another object of the invention is to provide an oil cracking process of the general character of the coil and drum type in which part of the heat of combustion of the heating coil furnace may be employed, through the medium of the heated oil in transit through a closed coil submerged in the body of oil in the lower portion of the bubble tower or towers, for maintaining such temperatures of the oil as are desired in effecting a close fractionation or separation of the lighter and heavier constituents.

More specifically it is an object of the present invention to closely divide or fractionate the vaporous hydrocarbon products received into the bubble tower or towers into two distinctly different products, the lighter of which is desired to have an end point sub-

stantially equal to that of the initial boiling point of the heavier constituents.

Still another object of the invention is to provide a process of this general character in which the operating pressure of the bubble tower or towers may preferably be progressively and substantially reduced below that existing in the heating coil and drum, thereby permitting a readier liberation of the lighter constituents from the heavier in effecting a close fractionation of the products.

Other objects, together with these, may be better understood from the following description and the accompanying drawing:

Broadly and generally the present invention contemplates subjecting the evolved vapors from the cracking zone to dephlegmation or fractionation and passing a portion of the hot products from the heating zone or the highly heated oil in transit to the cracking zone, through a heat exchange element positioned in the dephlegmator or fractionating tower to thereby maintain the liquid condensate therein at a vaporizing temperature to thereby free the said condensate from lower boiling constituents.

It is to be further understood that I have in mind accomplishing within the dephlegmator, fractionating tower or rectifier, the complete rectification of the vapors evolved from the cracking zone, on the one hand condensing and withdrawing such heavier constituents as it is desired to remove from the incoming vapors, while on the other hand, and while freeing the total heavier constituents from the said vapors, to conduct the total lighter vaporous constituents throughout the remainder of the system in the regular course of the process.

The accompanying drawing illustrates an apparatus embodying certain novel features and adapted for carrying out the process disclosed herein, although it will be understood that any form of suitable apparatus may be used in carrying out said process.

Referring to the drawing:

There is provided an elongated heating coil 1, which might be called a primary heating coil, of restricted cross section, through which oil is passed and heated in transit, deriving heat from the furnace 2, disposed beneath the coil and fired by the burner 3.

The hot oil emerging from the coil 1 may be conducted through a heat insulated pipe 5 and through the closed coil 15 within the bottom of the bubble tower 16 wherein a body of oil collects, being the condensed heavier constituents, which may have in addition a certain percentage of lighter constituents which is desirable to liberate for commingling and passing on with the other vaporous lighter constituents.

While operating the apparatus it may be desired to direct the flow of hot oil away

from the coil 15 so a by-pass has been provided for in the valve 4, pipe 7, valve 8, and valve 6, whereby the hot oil in continuous circulation may be returned to the secondary heating coil 9 for further heating 70 and disposal as will be hereinafter described.

The hot oil in transit through the closed coil 15, and having a temperature of from 800° F. to 850° F., with an average of approximately 825° F., transmits a part of 75 its heat through said closed coil to the cooler oil reposing in a body in the bottom of the bubble tower. The cooler oil may have a temperature of slightly less than 750° F. when the coil 15 is not in use.

The hot oil, somewhat cooler upon emerging from the coil 15, may pass through a heat-insulated pipe 20 into the closed coil 25 imposed within the bottom of another bubble tower 30, wherein also a body of oil collects, it being condensed heavier constituents, which may have in addition a certain percentage of lighter constituents which it is desirable to liberate for commingling and passing on with the other vaporous lighter 90 constituents in course of still further process.

Here also while operating, it may be desired to direct the flow of hot oil away from the coil 25, so a by-pass has been provided for 95 in the valve 21, pipe 22, valve 23 and the valve 24, whereby the hot oil in continuous circulation may be returned to the secondary heating coil 9 through a heat-insulated pipe 26 for further heating and disposal as will be hereinafter described.

It is to be understood that this method and system may comprise one or more bubble towers for fractionating the products, and that mainly for descriptive reasons, the apparatus has been drawn, constructed and described, as comprising two such towers numbered 16 and 30.

It is to be further understood that in each successive tower or towers substantially similar results may be obtained through the use of the closed heating coil imposed in the bottom of the said tower or towers as may be obtained in the first tower 16, though at varying temperatures and in some instances preferably at lesser pressures.

In regular operation, the process being continuous, the condensed heavier constituents reposing in the bottom of the tower 16 in a regulated volume will normally be continuously withdrawn through a heat-insulated pipe 40 and the valve 39 and may be forced back into the system by the pump 41, preferably re-entering the system through the coil 9.

The hot oil emerging from the heating coil 9 is passed through a heat-insulated pipe 42 and the valve 43, and preferably enters the drum 50 through a pipe 44, and the drum 51 through a pipe 45, although it may be desired 130

to effect an entry for the hot oil into the drums 52 and 53 also.

The vaporous products from the hot oil undergoing cracking in the drums 50, 51 and 52 pass successively through the upper portions of the drums near their tops and through the vapor communicating lines 54, 56 and 58 into the upper portion of drum 53, and the hot oil undergoing cracking overflows from 10 the drum 50 into the drum 51 and from the drum 51 into the drum 52 etc. through the equalizing lines 55, 57 and 59, while the residual products collecting in the drums in regulated volumes may be withdrawn through 15 the pipes 80, 82, 84, and 86, and the valves 81, 83, 85, and 87, connecting with the pipe 88.

The issuing vapors from the drum 53 are conducted through a heat-insulated pipe 70 and discharged into the bubble tower 16, 20 preferably entering at an intermediate point above the regulated level of the body of liquid reposing in the bottom of the tower. A pressure regulating valve 71 is provided in the line 70 whereby the pressure within the 25 bubble tower 16 may be reduced if desired from that existing in the drums 50, 51, 52, and 53, and the heating coils.

The vaporous products entering the tower 16 at a temperature of approximately 750° F. 30 are subjected to fractionation therein, the heavier constituents together with a portion of the lighter, condensing and dropping to the bottom of the tower wherein said condensate may be subjected to additional heating applied by the exchange of heat from the oil flowing through the coil 15, the temperature thereby being substantially increased. By such increase in temperature, a vaporization of the condensed lighter constituents may 35 be effected, the lighter constituents as vapors will rise, and rising and commingling with the uncondensed lighter constituents undergo a progressive lowering of temperature until they pass out near the top of the tower 16 40 through a heat-insulated pipe 100 at a temperature of approximately 450° F. It is thus to be seen that a fractionating or bubble tower condition is effected wherein progressively decreasing temperatures obtain from 50 the bottom to the top of the tower.

It should be pointed out that the temperatures as given herein are merely for descriptive purposes and are not intended as limitations to the scope of the present invention.

55 The vapors emerging from the bubble tower 16 through the heat-insulated pipe 100, enter the bubble tower 30 preferably at some intermediate point above the regulated level of liquid reposing in the bottom of the latter 60 tower. A pressure regulating valve 101 is provided in the line 100 whereby the pressure within the bubble tower 30 may be reduced if desired from that existing in the bubble tower 16.

65 The vaporous products upon entering the

tower 30 may be fractionated or separated, the lighter from the heavier constituents, in substantially the same manner as in the tower 16, except that the temperatures and pressures may be lower, thereby causing a difference in 70 the resulting products. The heavier constituents in repose as residual condensate in the bottom of the tower 30 may be withdrawn through the pipe 103 and the valve 104, while the lighter constituents as a vapor may 75 emerge from near the top of the tower.

The vapors issuing from near the top of the tower 30 pass through a pipe 105 and through the water condenser coil 106, the condensate and fixed vapors or gases emerging from said condenser coil passing through a pipe 107 into the collecting tank 108, which is provided with a gas outlet 110 and a valve 109 and a liquid discharge outlet 112 and a valve 111.

Although this invention as set forth does 80 embody more or less specific details of construction and operation, it should be understood that many variations may be effected without departing from the spirit and scope 85 of the invention.

What I claim is:

1. The process of converting higher boiling hydrocarbon oils into lower boiling ones that comprises passing the oil under superatmospheric pressure through a primary and a secondary heating coil wherein the oil is heated to a cracking temperature, delivering the heated oil into an enlarged chamber wherein a body of oil is maintained under cracking temperature and pressure, passing 95 the evolved vapors to a fractionating tower and subjecting said vapors to fractionation therein to form an overhead vapor fraction and a liquid condensate, passing highly heated oil from the primary heating coil through 100 a closed coil in contact with the liquid condensate collected in the bottom of the fractionating tower to thereby maintain the condensate at a vaporizing temperature.

2. The process of converting higher boiling hydrocarbon oils into lower boiling ones which comprises passing the oil through a heating coil to raise it to a cracking temperature under superatmospheric pressure, discharging the highly heated oil into an enlarged chamber in which cracking and vaporization takes place, conducting evolved vapors to a fractionating tower and subjecting them to fractionation therein to form an overhead vapor fraction and a final liquid 110 condensate, collecting the final liquid condensate in the lower portion of the fractionating tower, passing a portion of the highly heated oil from the heating coil, before it has been discharged into the enlarged 115 chamber, through a coil in contact with the liquid condensate collected in the lower portion of the fractionating tower and returning this portion of heated oil to the heating coil 120 for further heating.

3. The process of converting higher boiling hydrocarbon oils into lower boiling ones which comprises heating the oil to a cracking temperature under superatmospheric pressure in a series of coils, delivering the highly heated oil into a series of drums wherein cracking temperature and pressure is maintained, conducting evolved vapors to a fractionating tower wherein the pressure is reduced and subjecting the said vapors to fractionation therein, conducting a portion of the highly heated oil that has been raised to a cracking temperature through a heating coil submerged in the liquid condensate collected in the fractionating tower and returning this portion of heated oil to the series of oils for further heating.

4. The process of converting higher boiling hydrocarbon oils into lower boiling ones that comprises passing the oil raised to a cracking temperature through cracking drums, conducting the vapors to a fractionating tower, taking off an overhead vapor, holding in transit a regulated quantity of liquid condensate, introducing fresh charging stock into a primary heating coil, highly heating the oil therein, passing the heated oil through a coil submerged in the liquid condensate in the tower, conducting the oil upon emerging from said coil through a secondary heating coil wherein the oil is further heated to a cracking temperature and delivered to the cracking drums.

5. Apparatus for cracking hydrocarbon oils comprising a secondary heating coil, a cracking chamber in communication therewith, a fractionating tower in vapor communication with the cracking chamber, and having space for retaining a regulated quantity of liquid condensate therein, a closed heating coil in contact with the liquid condensate, means for conducting hot oil from a primary heating coil to the said closed coil in contact with the liquid condensate, means for returning the oil from the closed heating coil to the secondary heating coil wherein the oil is heated to a cracking temperature.

6. Apparatus of coil and drum type for cracking higher boiling hydrocarbon oils under superatmospheric pressure, comprising a primary and a secondary heating coil in series, a series of cracking drums, a pipe having branches establishing communication from the secondary heating coil to several drums of the series, a fractionating tower in vapor communication with the series of cracking drums, means for regulating the pressure within the fractionating tower, means for heating a body of liquid condensate collecting within the fractionating tower and means for returning the liquid condensate to the secondary heating coil.

In witness whereof I have hereunto set my hand this 11th day of January, 1928.
